REFRIGERATING APPARATUS

Lawrence A. Philipp, Detroit, Mich., assignor to
 Kelvinator Corporation, Detroit, Mich., a corporation of Michigan

Application March 13, 1935, Serial No. 10,910

11 Claims. (Cl. 62—2)

My invention pertains to refrigerating systems of the expansion type and more particularly to refrigerant flow controlling means therefor, and is an improvement upon the construction shown 5 in my copending application Serial No. 728,514 filed June 1st, 1934, which contains claims that dominate the present invention.

It is an object of my invention to provide regulating means for controlling the flow of liquid refrigerant from the high side of an expansion refrigeration system to the low side comprising a liquid receiving chamber for receiving and storing liquid refrigerant from the compressor, an open top bucket float in the 15 chamber, a valve actuated by the float for discharging liquid refrigerant therefrom, and syphon means arranged for intermittently charging the bucket float with a quantity of refrigerant from the chamber which is thence discharged 20 into the evaporator.

It is also an object of my invention to provide for such a system a refrigerant flow controlling means wherein a flow controlling valve piston is actuated by and guides the movements of an 25 open top bucket float which carries a syphon in its side wall for charging the float from an enclosing chamber.

Another object of my invention is to provide for systems of the above type a refrigerant flow 30 controlling means comprising a liquid storing chamber enclosing a bucket float having a restricted upwardly projecting portion and a valve actuated by the movements of the float for discharging liquid therefrom in conjunction with a 35 syphon disposed in the restricted portion for charging the float from the chamber.

It is a further object of my invention to provide a refrigerating system of the above type with refrigerant flow controlling means between 40 the high side and the low side comprising means for intermittently discharging stored quantities of liquid refrigerant to the low side and having associated means for conducting refrigerant vapor from the low side in heat exchange relation 45 with the stored liquid refrigerant for subcooling it prior to its discharge to the low side.

The invention itself, however, both as to its organization and its method of operation, together with additional objects and advantages 50 thereof, will best be understood from the following description of specific embodiments, when read in conjunction with the accompanying drawings, in which:

Fig. 1 is a view showing a section of my 55 refrigerant flow controlling means and diagrammatically representing an associated refrigerating system regulated thereby; and

Fig. 2 is a sectional view showing another embodiment of the refrigerant regulating device.

60 Referring more specifically to Fig. 1 of the

drawings the apparatus comprises a refrigerant compressor 11 for drawing refrigerant vapor from an evaporator 13 condensing the same, and compressing it through a suitable condenser 15 where its latent heat of vaporization is dissipated and the vapor is condensed to a liquid. The compressor 11 may be driven by an electric motor 17 which is energized from service line conductors L1 and L2 through the contacts 18 and 19 of a thermostatic snap acting switch 21 which is actuated in response to the temperature variations of the evaporator by a thermobulb 28 disposed adjacent thereto and connected with the switch through a suitable conduit 29. 5

For controlling the flow of liquefied refrigerant 15 from the condenser coils 15 to the evaporator 13 my flow controlling device 26 is connected therebetween. The flow controlling device comprises a liquid receiving chamber or valve casing 27 which may consist of a substantially cylindrical 20 sheet metal shell which is closed at the bottom and open at the top. The open top of the valve casing 27 is closed by a cover plate 29 which is of relatively heavy construction and is clamped securely thereon by nuts 31 threadably engaged 25 upon bolts 33 which project through the cover 29 from the shell 27. If desired a suitable resilient material or gasket may be introduced between the upper edge of the shell 27 and the cover 29 to provide a hermetically tight seal 30 therebetween in a well known manner.

In order that conduit means 35 extending from the refrigerant condenser 15 may be conveniently connected to the flow controlling device 26, a suitable pipe fitting 37 is inserted through 35 the wall of the valve chamber 27 to which it may be hermetically secured in any suitable manner, as by welding for example.

The outlet connection from the flow controlling device comprises a conduit 39 threadably supported in the cover plate 29 from which it projects downwardly into the chamber. The upper end of the outlet conduit 39 is provided with a suitable pipe fitting 41 for connection with the refrigerant distributing line 43 which extends to 40 the evaporator 13. A downwardly inclined baffle 99 is secured on the inside of the casing 27 above the inlet fitting 37 to deflect the entering refrigerant downwardly away from the upper portion of the float. The outlet conduit 39 is provided with an enlarged portion providing a shoulder 43 below the threaded portion for abutting the lower surface of the cover 29. 45

Within the chamber 27 I provide a bucket float 45 comprising a cup shaped member which 55 carries a valve piston member 47 rigidly secured to the bottom thereof and projecting upwardly into the lower end of the depending outlet conduit 39 which opens adjacent the bottom of the float. The bucket float may be of sheet metal 60

to the bottom of which the valve piston 47 may be secured in any suitable manner as by a nut 48 threadably engaged on a small threaded portion of the piston 47 which extends through the bottom of the float. The upper end of the valve piston is tapered for cooperatively engaging an annular valve seat 49 which is disposed within a restricted portion 51 of the outlet conduit. The aperture above the valve seat 49 and the restricted portion 51 is suitably expanded to provide for efficiently conducting the discharged refrigerant to the line 43 which is the low side of the system.

The valve piston 47 is smaller than the inside diameter of the conduit 39 in which it is slidably received to provide sufficient space therebetween for the passage of refrigerant, and at its lower end the aperture in the conduit is substantially enlarged to receive an annular guide ring 53 which is adapted to fit the valve piston 47 in snug guiding relation while permitting free movement thereof. The guide ring 53 is provided with numerous perforations 55 to permit the liquid refrigerant to flow freely into the lower end of the conduit 39 when the valve is opened. The length of the valve piston member 47 and the position of the valve seat 49 within the conduit are so arranged that the valve is open when the float 45 is in its lowest position 30 in the valve casing chamber 27, and when the float 45 is buoyed up by the liquid in the chamber its movement upwardly is limited by the engagement of the tapered end of the valve piston with the valve seat, which thereby closes 35 the valve and restricts the admission of the refrigerant liquid to the outlet conduit 39.

For charging the bucket float 45 with liquid refrigerant from the liquid receiving valve chamber 27 I provide a siphon conduit 57 comprising a substantially U shaped conduit which passes through a side wall of the float in inverted position. One leg 59 of the siphon conduit 57 extends down the outside of the float 45 and the other leg 61 projects down the inside thereof to 45 a lower level. A piece of metal 63 is secured to the outer sidewall of the float diametrically opposite the siphon to counterbalance the weight thereof on the float.

In operation the compressor 11 is intermittently actuated by the thermostatic switch 21 to supply sufficient refrigerant to maintain the temperature adjacent the evaporator 13 within a predetermined range. As the liquefied refrigerant passes down from the condenser coils 15 through the conduit 35 it accumulates in the valve chamber 27 where it lifts the bucket float 45 thereby closing the valve. As the level of the liquid continues to rise in the valve chamber, it primes the siphon 57 when it is level with the loop thereof. After the siphon has thus been automatically primed the liquid flows from the chamber 27 into the float 45 which loses buoyance and when it has been charged with a certain quantity of the liquid sinks to the bottom 65 of the valve casing 27, thereby opening the needle valve 47, 49.

The siphon continues to operate until the level of liquid within the outer valve chamber 27 has been reduced to a position adjacent the lower end of the adjacent siphon leg 59. The opening of the valve 49 discharges the charge of liquid refrigerant from the bucket float into the outlet conduit 39 from which it passes through the low side line 43 to the evaporator 13. The 75 float then gains buoyance and lifts the valve

piston 47 thus reclosing the valve. Thus a dumping action float is obtained which requires no weight feed valve at the evaporator.

For subcooling the quantity of liquid refrigerant stored in the valve chamber and the bucket float an annular jacket member 71 of sheet metal is secured around the lower portion of the valve casing 27 and comprises a substantially cylindrical sheet metal member closed at one end and open at the other end. The jacket member 71 is of a diameter substantially larger than that of the valve casing 27 over which it is disposed in concentrically spaced relation and to which the upper edge is hermetically secured in any suitable manner, as by welding. A pipe fitting 13 is inserted through the upper wall of the jacket 71 for convenient connection with the suction line 75 extending from the evaporator 13. A second pipe fitting 77 is inserted through the jacket wall at a position preferably adjacent the bottom thereof for convenient connection with the suction line 79 which extends to the compressor 11.

The cold refrigerant vapor withdrawn from the evaporator 13 is thus conducted in intimate heat exchange relation around the lower portion of the valve casing 27 and efficiently sub-cools the quantity of liquid refrigerant stored therein.

In accordance with another embodiment of my invention the bucket float for controlling the valve has an annular upper wall 81 provided with a restricted neck portion 83 projecting upwardly therefrom, as shown in Fig. 2. In this embodiment of my invention, a siphon 85 is disposed through the wall of the neck portion 83 of the float, and the float is charged with liquid when its level in its outer casing 27 rises to a relatively high level above the siphon 85 in the neck of the float. With this arrangement, as in that previously described, the outer projecting leg 87 of the siphon 85 is preferably shorter than the other leg 89 of the siphon which projects down to a lower level within the float.

In accordance with this embodiment of my invention a tubular guide member 91 is rigidly secured to the bottom of the float, in any suitable manner, and rises therefrom in concentrically disposed relation around the outside of the outlet conduit 39 where it serves to guide the movements of the float. A valve piston member 93 is secured to the tube guide member 91 by means of a suitable cross pin 95 extended therethrough. The liquid refrigerant is admitted to the lower end of the guide tube 91 through apertures 97 therein adjacent the bottom of the float.

In this embodiment the valve piston 93 serves only to regulate the flow of liquid refrigerant from the float, and the tubular guide member 91 cooperates with the outlet conduit 39 to guide the movements of the float. The connection of this device into the refrigerating system and its operation therein is similar to that previously described with reference to the embodiment shown in Fig. 1.

It will be seen that I have provided a refrigerant flow controlling device of simple construction in which a dumping action float is obtained requiring no weight feed valve at the evaporator and eliminating the difficulties prevalent in the refrigerant flow controlling arrangements comprising small orifices for metering the flow of refrigerant from the high side to the low side of the system.

Aside from the specific embodiments of the invention herein shown and described, it will be understood that numerous details of the con- 75

struction may be altered or omitted without departing from the spirit and scope of the invention as disclosed and claimed, and that I do not desire to limit the invention to the exact constructions herein set forth.

I claim as my invention:

1. In combination in a refrigerant flow controlling device, a liquid storing chamber, an inlet port therein for receiving refrigerant, a bucket float in said chamber, conduit means opening adjacent the bottom of said float and arranged for restriction by the motion of the float as it is lifted by liquid in the chamber, and a siphon for charging the float with a quantity of liquid from the chamber.

2. In combination in a refrigerant flow controlling device, a liquid storing chamber, an inlet port therein for receiving refrigerant, a bucket float in said chamber, conduit means opening adjacent the bottom of said float and arranged for restriction by the motion of the float as it is lifted by liquid in the chamber, said conduit means also serving to limit the upward movement of said float, and a siphon carried by said float for charging the float with a quantity of liquid from the chamber.

3. In combination in a refrigerant flow controlling device, a liquid storing chamber, an inlet port therein for receiving refrigerant, a bucket float in said chamber, conduit means opening adjacent the bottom of said float and arranged for restriction by the motion of the float as it is lifted by liquid in the chamber and a siphon for charging said float with a quantity of liquid from the chamber comprising a substantially U shaped conduit projecting through one wall of said float in inverted position with a short leg extending down the outside of said wall and a longer leg projecting down the inside of said wall.

4. In combination in a refrigerant flow controlling device, a liquid storing chamber, a bucket float therein, a conduit depending into said float and opening adjacent the bottom thereof, a valve associated with said conduit for restricting flow therein comprising a slideable valve piston secured to the bottom of said float for actuation thereby while guiding the float in its movements in the chamber, said valve piston also limiting the uppermost position of the float in the chamber, a siphon conduit inserted through a side wall of said float and having downwardly projecting legs on opposite sides thereof.

5. In combination in a refrigerant flow controlling device, a liquid storing chamber, a bucket float therein, said float comprising an open top cup shaped vessel, a conduit depending into said float and opening adjacent the bottom thereof, a valve associated with said conduit for restricting flow therein comprising a slideable valve piston secured to the bottom of said float for actuation thereby while guiding the float in its movements in the chamber, said valve piston also limiting the uppermost position of the float in the chamber, a siphon conduit inserted through a side wall of said float for charging the float with a quantity of liquid from the chamber comprising a substantially U shaped conduit disposed in inverted position with a short leg extending down the outside of said wall and a longer leg projecting down the inside of said wall.

6. In combination in a refrigerant flow con-

trolling device, a refrigerant receiving chamber, a bucket float therein, having a restricted portion extending upwardly in open relation with the interior of the float, a conduit member depending through said restricted portion into said float and opening adjacent the bottom thereof, and a siphon disposed through the wall of the restricted portion of said float for charging the float with a quantity of liquid from said chamber.

7. In combination in a refrigerant flow controlling device, a refrigerant receiving chamber, a bucket float therein having a restricted portion extending upwardly in open relation with the interior of the float, a conduit member depending through said restricted portion into said float and opening adjacent the bottom thereof, a tubular guide slidably disposed in concentric relation around said conduit member and secured at its lower end to the bottom of said float, an open portion provided in the lower end of said tubular guide, a valve piston slidably disposed in the lower end of said conduit for actuation by said float.

8. In combination in a refrigerant flow controlling device, a liquid storing chamber, a valve in said chamber, float actuating means responsive to the level of liquid in the chamber for intermittently actuating said valve to discharge quantities of liquid therefrom, and a jacket disposed in intimate thermal coupled relation around the lower portion of said chamber.

9. In combination in a refrigerant flow controlling device, a liquid storing chamber, a bucket float in said chamber, a valve actuated thereby for discharging liquid therefrom, a siphon for intermittently charging said float with liquid from said chamber to actuate said valve, and a jacket disposed in intimate thermal coupled relation around the lower portion of said chamber.

10. A refrigerating system comprising a refrigerant evaporator, a refrigerant compressor for withdrawing refrigerant vapor from said evaporator condensing the same and supplying liquid refrigerant thereto, a refrigerant flow controlling device interposed between said compressor and evaporator comprising a liquid storing chamber, a bucket float in said chamber, a valve actuated thereby for discharging liquid therefrom, a siphon for intermittently charging said float with liquid from said chamber to actuate said valve, and a jacket disposed in intimate thermal coupled relation around the lower portion of said chamber, and conduit means for passing the discharged quantities of refrigerant to said evaporator and the withdrawn refrigerant vapor through said jacket.

11. A refrigerating system comprising a refrigerant evaporator, a refrigerant compressor for withdrawing refrigerant vapor therefrom, condensing the same, and supplying liquid refrigerant thereto, interconnected flow controlling means for regulating the flow of liquid refrigerant to said evaporator comprising a liquid storage chamber, a bucket float in said chamber, a valve actuated thereby for discharging liquid therefrom and a siphon carried by said float for charging the ~~same~~ with liquid from said chamber whereby the valve is intermittently actuated to discharge quantities of refrigerant to said evaporator.

LAWRENCE A. PHILIPP.
